DESIGN FOR A MULTIPLE SPRAY GUN

John W. Baur, Chicago Ill., assignor to Binks
Manufacturing Company, Chicago, Ill., a cor-
poration of Delaware

Application February 7, 1945, Serial No. 117,801

Term of patent 14 years

(Cl. D62—2)

To all whom it may concern:

Be it known that I, John W. Baur, a citizen of the United States and residing at Chicago, county of Cook, and State of Illinois, have invented a new, original, and ornamental Design for a Multiple Spray Gun, of which the following is a specification, reference being made to the accompanying drawings, forming a part thereof.

Fig. 1 is a front end view in elevation of the multiple spray gun showing my new design;

Fig. 2 is a side view in elevation of the same;
Fig. 3 is a top plan view thereof;
Fig. 4 is a bottom plan view thereof; and
Fig. 5 is a rear end view in elevation thereof.

I claim:

The ornamental design for a multiple spray gun, as shown.

JOHN W. BAUR.
